UNITED STATES PATENT OFFICE

2,452,727

TIE RACK

George C. Burton, Washington, D. C.

Application July 3, 1947, Serial No. 758,915

2 Claims. (Cl. 211—124).

1

This invention relates to an improved construction of rack for neckties or other articles adapted to be hung in a folded position and has for its primary object to provide a rack including yieldable gripping means for effectively holding a tie or other article suspended thereover until forcibly removed to thereby afford means which will positively prevent a necktie or other article from accidentally sliding off of the rack.

More particularly, it is an object of the invention to provide a rack including a supporting member which is yieldably mounted and which forms a yieldable clamping element.

Various other objects and advantages of the invention will hereinafter become more fully apparent from the following description of the drawing, illustrating a preferred embodiment thereof, and wherein—

Figure 1 is a front elevational view of the rack;

Figure 2 is a top plan view, partly in section thereof;

Figure 3 is a cross sectional view thereof taken substantially along a plane as indicated by the line 3—3 of Figure 1;

Figure 4 is a fragmentary end elevational view looking toward the back side of the rack;

Figure 5 is a cross sectional view of the rack along a plane as indicated by the line 5—5 of Figure 1;

Figure 6 is a longitudinal sectional view taken substantially along a plane as indicated by the line 6—6 of Figure 5, and

Figure 7 is an enlarged fragmentary cross sectional view taken substantially along a plane as indicated by the line 7—7 of Figure 1.

Referring more specifically to the drawing, the tie rack in its entirety is designated generally 10 and includes an elongated, substantially flat base member 11 to the forward side of which is secured two fixed clamping members 12 and 13 by suitable fastenings 14 which extend through the base 11 and into said members 12 and 13. The corresponding members 12 and 13 are of circular cross section and are disposed longitudinally of the base 11 and in parallel abutting engagement as best seen in Figures 3 and 7.

As best seen in Figures 2, 5 and 6, the fixed clamping members 12 and 13, adjacent each of the ends thereof, are provided with opposed recesses forming bores 15 which align with openings 16 in the base 11.

A supporting bar 17, which corresponds in length, cross sectional shape and size to the fixed clamping members 12 and 13 is disposed against the outer sides thereof and partially in the cavity

2

therebetween, as seen in Figure 3, and said rod 17, adjacent its ends, is provided with inwardly opening transverse recesses 18 which register with the bores 15. An anchoring pin 19 extends inwardly from each end of the rod 17 transversely through the recess 18, adjacent said end, and each of said pins forms an anchor for an end of a contractile coil spring 20. The coil springs 20 are provided with eyes at the ends thereof and the anchoring pins 19 extend through corresponding eyes of the springs 20. The springs 20 extend inwardly from the recesses 18 through the bores 15 and into the openings 16 and the eyes, at the opposite ends thereof, are engaged by the intermediate U-shaped portions 21 of anchoring pins 22, having substantially straight end portions which bear against the back or rear face of the base 11 and with the intermediate portions thereof extending into the openings 16.

The base 11 may be secured in any suitable manner to an upright supporting surface, such as a wall as by means of eye fastenings 23 which project from the upper edge thereof and which are adapted to engage hooks, nails or other suspending means, not shown, in an upright supporting surface for suspending the rack 10 thereagainst.

It will be readily obvious that the springs 20 will yieldably retain the supporting rod 17, between 30 and against the outer sides of the fixed clamping members 12 and 13 or in the position as illustrated in Figures 2 and 3. To apply a necktie 24 or other article to be supported on the rack 10, the supporting rod 17, which forms the movable clamp element, is pulled outwardly and away from the fixed clamp elements 12 and 13 against the action of the springs 20, so that the necktie or other article 24 can be inserted between said rod 17 and the elements 12 and 13 and suspended over the rod 17. When the rod 17 is released, the springs 20 return it to its position of Figure 7, and so that a portion of the tie 24 will be clamped between said rod 17 and the fixed clamp elements 12 and 13. Accordingly, it will be readily apparent that said portion will be yieldably clamped so as to prevent the tie 24 from accidentally sliding off of the supporting rod 17 even though clamped adjacent one end thereof and so that the weight of the other end would normally be sufficient to 50 cause the tie to slide off of the rack. By manually engaging and pulling the rod 17, away from the elements 12 and 13, it will be readily apparent that the tie 24 can be removed.

Obviously, any number of ties 24 may be simultaneously supported as previously described and

as illustrated in Figures 1 and 7, and other articles, not shown, such as towels may be hung upon the rod 17 of the rack and similarly clamped.

The rack 10 may be formed of any suitable material, the parts 11, 12, 13 and 17 preferably being formed of wood, although other materials may be employed.

Various modifications and changes are contemplated and may obviously be resorted to, without departing from the spirit or scope of the invention as hereinafter defined by the appended claims.

I claim as my invention:

1. A supporting rack of the character described, an elongated base adapted to be secured to a supporting surface, two fixed clamp elements of circular cross section secured to the forward side of said base and disposed longitudinally thereof and in parallel, abutting engagement, a rod of circular cross section engaging uniformly against the outer portions of said fixed clamping elements and extending into the outwardly opening cavity therebetween, and resilient means for connecting said rod to the base and for yieldably mounting said rod relatively to said fixed clamping elements and for movement in directions toward and away from the fixed clamping elements, said resilient means comprising contractile coil springs disposed adjacent the ends of the base, fixed clamp elements and rod, said base and fixed clamp elements being provided with aligned bores to receive said springs, and means for anchoring the ends of the springs to said rod and base.

2. A supporting rack of the character described, an elongated base adapted to be secured to a sup-

porting surface, two fixed clamp elements of circular cross section secured to the forward side of said base and disposed longitudinally thereof and in parallel, abutting engagement, a rod of circular cross section engaging uniformly against the outer portions of said fixed clamping elements and extending into the outwardly opening cavity therebetween, and resilient means for connecting said rod to the base and for yieldably mounting said rod relatively to said fixed clamping elements and for movement in directions toward and away from the fixed clamping elements, said resilient means comprising contractile coil springs disposed adjacent the ends of the base, fixed clamp elements and rod, said base and fixed clamp elements being provided with aligned bores to receive said springs, and means for anchoring the ends of the springs to said rod and base, said anchoring means including recesses formed transversely of said rod and into which corresponding ends of the springs extend, and anchoring pins extending longitudinally of said rod and transversely through said recesses for engaging and anchoring said ends of the springs.

Certificate of Correction

Patent No. 2,452,727.

November 2, 1948.

GEORGE C. BURTON

It is hereby certified that error appears in the above numbered patent requiring correction as follows:

In the grant, line 6, title of invention, for "TIRE RACKS" read *TIE RACKS*; and that the said Letters Patent should be read with this correction therein that the same may conform to the record of the case in the Patent Office.

Signed and sealed this 28th day of December, A. D. 1948.
